M. F. CURRIE

Des. 164,846

HAIR CURLER

Filed March 29, 1950

Inventor

Margaret F. Currie

UNITED STATES PATENT OFFICE

164,846

HAIR CURLER

Margaret F. Currie, Manhasset, N. Y.

Application March 29, 1950, Serial No. 8,831

Term of patent 14 years

(Cl. D86—10)

To all whom it may concern:

Be it known that I, Margaret F. Currie, a citizen of the United States, residing at Manhasset, county of Nassau, and State of New York, have invented a new, original, and ornamental Design for Hair Curlers, of which the following is a specification, reference being had to the accompanying drawing, forming a part hereof.

The single figure is a perspective view of the hair curler showing my design.

I claim:

The ornamental design for a hair curler, as shown.

MARGARET F. CURRIE.
